UNITED STATES PATENT OFFICE.

HELENE M. RICHARDOT, OF DETROIT, MICHIGAN.

DESIGN FOR A HOOD.

41,484.

Specification for Design. Patented June 13, 1911.

Application filed September 22, 1910. Serial No. 583,311. Term of patent 7 years.

To all whom it may concern:

Be it known that I, HELENE M. RICHARDOT, a citizen of the United States of America, residing at Detroit, in the county of Wayne and State of Michigan, have invented a certain new, original, and ornamental Design for Hoods, of which the following is a specification, reference being had therein to the accompanying drawings, forming part thereof, in which—

I claim:

The ornamental design for a hood, as shown.

HELENE M. RICHARDOT.

Witnesses:

JAMES P. BARRY,
AUBREY PULLEYBLANK.
